UNITED STATES PATENT OFFICE.

EDWIN J. PRINDLE, OF EAST ORANGE, NEW JERSEY, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-LAST.

1,261,436.

Specification of Letters Patent.

Patented Apr. 2, 1918.

Original application filed May 10, 1913, Serial No. 766,811. Divided and this application filed January 2, 1915. Serial No. 165.

To all whom it may concern:

Be it known that I, EDWIN J. PRINDLE, a citizen of the United States, residing at East Orange, in the county of Essex and 5 State of New Jersey, have invented certain Improvements in Shoe-Lasts, of which the following description, in connection with the accompanying drawings, is a specification, like reference characters on the drawings indicating like parts in the several figures.

This invention relates to lasts, and particularly to lasts having a removable heel part to provide, for example, for removal of 15 the heel part while the forepart remains in the shoe in order to facilitate heelng on the jack, or the substitution of a filler heel part after those operations which require a very strong and rugged heel part have been 20 completed by the aid of such heel part.

The general object of the present invention is to provide a last of the type having separable fore and heel parts which will have all the above-named and other advantages 25 characteristic of lasts of this type as heretofore constructed and which will be at the same time stronger, simpler in construction and consequently cheaper to manufacture, and more readily manipulated and operated than lasts of the type heretofore known.

A feature of the invention is a hinge connection comprising headed studs on different levels on one of the two separable parts 35 (there being one or several studs on any level, as desired) and a hinge plate on the other last part having notches in different planes substantially parallel to the plate, to engage the studs. This arrangement of the 40 notches permits them to be easily seen by the operator while removing or attaching the heel part while the forepart is in the shoe, these operations being difficult under such circumstances since the cramped quarters 45 interfere greatly with ease in manipulation. In the last shown in the drawings, the studs are arranged with the lower farther to the rear than the upper. This structure admirably serves the purpose described.

50 The invention also comprises a novel bonding means for holding the last parts together when in extended position. This means comprises a member on one last part

and two members on the other last part constructed and arranged to engage and grasp 55 the former member between them. In the last shown, one of the latter two members is a hinge plate which moves relatively toward the other as the hinge expands to extended position.

60 Another feature of the invention consists in a novel locking means for a hinge last, comprising a bail attached to one part of the last and a hook shaped arm mounted on the other last part and engaging the bail 65 so that the arm is always held against accidental displacement from its normal operative path.

These and other features of the invention 70 will be understood from the following description of a preferred embodiment thereof, selected for purposes of illustration.

In the accompanying drawings,

Figures 1, 2 and 3 are, respectively, a plan view and longitudinal sectional views of a 75 shoe last embodying my invention;

Fig. 4 is a side elevation of a shoe last embodying my invention;

Fig. 5 is a rear view of the toe part of 80 the last;

Fig. 6 is a transverse vertical sectional view of Fig. 1;

Figs. 7, 8 and 9 are, respectively, front, side and back views of the forward plate of 85 my hinge connection;

Figs. 10, 11 and 12 are similar views of the rear plate of my hinge plate connection;

Figs. 13 and 14 are front and side elevations of a locking piece; and

Figs. 15 and 16 are similar views of the 90 spring.

The last which is the subject of my invention is of the type having a toe and heel part readily detachable from each other so that a standard heel part can be used with 95 several or many styles of toe parts, thus reducing the cost of lasts in a factory, since not all the styles of toe parts are in use at the same time. For this style of last it is obviously desirable to have the heel part indestructible or as nearly indestructible as possible, because the greatest strains come upon the heel part. In the accompanying drawings, the toe part 1 is shown as connected with the heel part 2 by the following 100 connection: Headed studs 3 are secured in

the rear face of the toe part as by rivets 4, there preferably being one upper and two lower studs. These studs are adapted to be engaged by a forward plate 5 of a hinge 5 connection, which plate is shown in Figs. 7 to 9. The said plate 5 has two lower notches 6 which, like keyhole slots, are adapted to fit over and behind the heads of the lower studs 3, and it is provided with an 10 upper notch 7 that is preferably formed in the turned-over upper end 8 of the plate, such end at its sides having ears 8', to which are riveted ears 9 formed on the body of the plate. The notch 7 thus stands in a plane 15 forward of the notches 6 so that the said notch can be open at its bottom, instead of being a true keyhole slot, as it would have to be if it were formed in the body of the plate 5. This permits engagement of the 20 plate 5 with the three studs by a simple downward movement. The plate 5, at its lower end, has two ears 10 bent rearward therefrom, which are connected by rivets or a pintle 11 with ears 12 on the rear hinge 25 plate 13. At its upper end, the rear hinge plate has ears 14 in which is pivoted the U-shaped locking piece 15 shown in Figs. 13 and 14, as by a rivet or pintle 16. The locking piece is engaged under a bail 16' secured 30 in a vertical plane in the forward plate 5 as by having its ends passed through said plate and headed over. The U shape in which the member 15 is shown is regarded as preferable but, if desired, a hook arranged 35 to engage the bail 16' may be used. I regard the bail broadly as a hook. The lower end of the plate 13 is bent forward as at 13', so that when the hinge is open and the last extended, as in Fig. 2, said edge 40 13 will project under the heads of the lower studs 3, and thus lock the hinge connection from riding up and becoming detached from said studs. A spring 17, as shown in Figs. 15 and 16, has its front and rear ends 45 18 and 19, respectively, connected by a loop 20 which is only partially closed, so that said loop can be sprung over the pintle 16 and removably hold the spring in place, thus providing for its ready renewal in case of 50 breakage. The forward end 18 of the spring is preferably forked to straddle the bail in the collapsed condition of the hinge. The rear end of the spring rests against the plate 13, and the forward end under the legs of 55 the locking piece 15 so that the spring normally tends to throw the locking piece up. When the locking piece is thrown down, as shown in Fig. 3, and the hinge collapsed, the forward plate can be engaged with or 60 disengaged from the studs on the fore part by a simple vertical movement, because the portion 13' of the rear hinge plate is removed from beneath the studs. When the last is extended by opening the hinge, the

spring throws the locking piece to the upper 65 end of the bail, and in this position the locking piece prevents either collapse or a further extension of the last. The portion 13' of the rear hinge plate also engages the stud heads from below and thus locks the hinge 70 on the studs.

I do not describe or claim herein the novel construction of last heel disclosed, since I have claimed it in my application Serial No. 766,811, filed May 10, 1913, of which this 75 case is a division.

Having described my invention, what I claim as new and desire to secure by Letters Patent of the United States is:—

1. A hinge connection for shoe lasts comprising plates hinged together and arranged to be attached to the fore and heel parts, respectively, one of said plates having a bail attached thereto and the other having a substantially hook-shaped arm pivoted thereto 85 and adapted to engage said bail.

2. A hinge connection for shoe lasts comprising plates hinged together and arranged to be attached to the fore and heel parts, respectively, one of said plates having a bail 90 attached thereto and the other having a substantially hook-shaped arm pivoted thereto and adapted to engage said bail, and a spring normally tending to throw said arm away from the hinge axis. 95

3. A hinge connection for shoe lasts comprising headed studs at different levels on the toe part and forward and rear hinge plates hinged together, the forward hinge plate having downwardly extending notches 100 in different planes taken substantially parallel to the plate to engage said studs, a notch for a lower stud being rearward of a notch for an upper stud.

4. A hinge connection for shoe lasts comprising a toe part, headed studs thereon at different levels, the lower projecting farther to the rear than the upper, forward and rear hinge plates hinged together, the forward plate having a notch in its lower edge to 110 engage a lower stud, having its upper edge bent over and notched to engage an upper stud, and ears formed on said bent over portion and engaging the body of the plate. 105

5. A hinge connection for shoe lasts comprising a toe part, headed studs thereon at different levels, the lower projecting farther to the rear than the upper, forward and rear hinge plates hinged together, the forward plate having a notch in its lower edge to 115 engage a lower stud, having its upper edge bent over and notched to engage an upper stud, ears on the body of the plate, and ears formed on said bent over portion and secured to the ears on the body of the plate. 120

6. A hinge connection for shoe lasts comprising forward and rear plates hinged together in their lower portions, a bail secured 125

- to one of said plates, and a U-shaped locking piece secured to the other of said plates and engaging said bail.
7. A hinge connection for shoe lasts comprising forward and rear plates hinged together, a bail secured to one of said plates, a pintle secured to the other of said plates, a U-shaped locking piece engaging said bail and pivoted to said pintle, and a spring having a pair ally open bend and secured to the pintle by having said bend sprung over said pintle, said spring having one end resting against the latter plate, and the other end against said locking piece.
10. A hinge connection for shoe lasts comprising headed studs at different levels on one last part, and forward and rear hinge plates hinged together, one plate having notches in different planes taken substantially parallel to the main body of the plate and arranged to engage said studs.
15. A hinge connection for shoe lasts comprising headed studs at different levels on the toe part, the lower being substantially behind the upper, so as to be plainly visible and accessible from above, and a hinge plate mounted on the heel part, having downwardly extending notches, not all in the plane of the plate, to engage said studs.
20. A last comprising a fore part having a bonding member, a heel part having a pivoted bonding member constructed and arranged to move downwardly into engagement with said fore part bonding member, and a locking member on said heel part constructed and arranged to engage under said fore part bonding member in such manner that disengagement of said two bonding members is prevented.
25. A last including a fore part having a bonding member, and a heel part having bonding means comprising a pivoted member and a fixed member constructed and arranged to grasp said fore part bonding member between them, whereby said heel part is attached to said fore part.
30. A shoe last comprising a forepart, a heel part, a hinge connection between said parts, a bail secured to one of said parts, a hook-shaped arm pivoted to the other of said parts and arranged to engage said bail to hold the parts of the last in extended position.
35. In a shoe last, the combination of a toe part, a heel part, a hinged connection between them, and a locking piece adapted to hold said connection extended, said locking piece being in the form of a bail, a pintle on which the ends of said bail are mounted, and a spring having a contracted open loop adapted to be sprung over said pintle, and having one end arranged to bear under said locking piece and the other end arranged to rest against a fixed part of the last.
11. A hinge connection for shoe lasts comprising headed studs at different levels on the toe part, the lower being substantially behind the upper, so as to be plainly visible and accessible from above, and a hinge plate mounted on the heel part, having downwardly extending notches, not all in the plane of the plate, to engage said studs.
12. A last comprising a fore part having a bonding member, a heel part having a pivoted bonding member constructed and arranged to move downwardly into engagement with said fore part bonding member, and a locking member on said heel part constructed and arranged to engage under said fore part bonding member in such manner that disengagement of said two bonding members is prevented.
13. A last including a fore part having a bonding member, and a heel part having bonding means comprising a pivoted member and a fixed member constructed and arranged to grasp said fore part bonding member between them, whereby said heel part is attached to said fore part.
14. A last including a fore part having a bonding member, a heel part having a hinge connection arranged to engage said fore part, and pivotally related jaws operated by opening or closing said hinge connection, constructed and arranged to grasp said fore part bonding member.

In testimony whereof I have signed my name to this specification in the presence of two subscribing witnesses.
